1936

4 Claims. (Cl. 95—88)

The present invention relates to photographic developers.

One of its objects is to provide a photographic developer containing special hydroxyalkylamines.

5 Other objects will appear from the detailed specification following hereinafter.

For the development of latent photographic images, especially in halide silver emulsions, alkaline developers have long been used. The alkalinity of these developers consisting of a mixture of several substances normally is due to the presence of an alkali hydroxide or an alkali carbonate. A series of light-sensitive substances and photographic processes has been found and 10 introduced into the art which requires the use of substances of a smaller degree of alkalinity than, for example, caustic potash or soda. When inorganic carbonates are used the evolution of bubbles of gas (carbon dioxide) is likely to occur with injurious effect if the photographic material is transferred from the alkaline developer into an acid fixing bath or intermediate bath. For these reasons attempts have been made to find a suitable substitute for inorganic alkalies. 15

20 On several occasions triethanolamine (in the form of the free base or a salt thereof) as well as the hydroxyalkylamines generally have been suggested as a substitute. These compounds, which are essentially characterized by the group- 25

20 ing

=N.(CH₂)_xOH or —N[(CH₂)_xOH]₂ or
NI(CH₂)_xOH]₃

35 x being at least 1) also have a strong alkalinity and a tendency to absorb carbon dioxide. Moreover, all of these agents which are preferable for the purpose are liquid and many have a disagreeable odor and therefore are not suitable 40 for the production of developing mixtures for commercial use.

This invention is based on the observation that aliphatic hydroxyalkylamines which instead of only one hydroxyl group in one alkyl group contain in at least one alkyl chain two or several hydroxyl groups combined with different carbon atoms serve in a surprising manner as alkaline agents for photographic developers. They correspond generally with the formula

wherein

R₁=H or aralkyl or alkyl or hydroxyalkyl or polyhydroxyalkyl,

R₂=H or aralkyl or alkyl or hydroxyalkyl or polyhydroxyalkyl,

x=at least 1,

y=at least 2,

z=0 or 1 or more.

10 The hydroxyl groups may be free or etherified or esterified; internal ethers are also useful. It is necessary that the compound should be well soluble in water. Such polyhydroxyalkylamines are especially amino-derivatives of the sugars 15 and carbohydrates having 5 and 6 carbon atoms but also lower and higher homologues may be used. In the hydroxyalkyl chain the carbon atoms combined with the hydroxyl groups may also be separated by one or more C-atoms without a hydroxyl group. Without implying that 20 the other bodies conforming with the above formulae are unsuitable or little suitable, there may be mentioned here as especially suitable substances the following: glucamine, methyl-, ethyl-, 25 propyl-, dodecyl-glucamine, mannamine, galactamine, lactamine, fructamine, arabinamine, xylamine, 1- or 2-aminopropane diol.

Most of these compounds are easily and cheaply obtained from the sugars by aminating them 30 under reducing conditions, see for instance Richter-Anschütz, Chemie der Kohlenstoffverbindungen, I. 12, (1928), 742 and 751, and E. Roux, Bulletin de la Société Chimique de France (3) 25, 586 (1901), Comptes Rendus de l'Academie des 35 Sciences (1903) 1079, 1081 and Chemisches Zentralblatt (1904) I, 871. They are characterized by their low degree of alkalinity, by their very good solubility owing to their numerous hydroxyl groups and, particularly in the case of the compounds in which alkyl groups take the place of the hydrogen atoms at the nitrogen, by their 40 good wetting properties. Most of them are solid and odorless bodies, which properties make them especially advantageous for making trade packages. 45

These bodies may be used in all kinds of known developers, for example rapid developers, fine grain developers, blue and brown tint developers, 50 negative developers, positive developers, paper developers, reversal developers, and color developers used in the color development processes.

The following examples illustrate the invention:

EXAMPLE 1

Normal developer

5	Water	cc	1000
	1-hydroxy-4-methylaminobenzenesulfate	gram	1
	Hydroquinone	grams	3
	Dry sodium sulfite	do	13
10	Methylglucamine	do	25
	Potassium bromide	gram	1

EXAMPLE 2

Blue-black developer

15	Water	cc	1000
	1 - hydroxy - 4-methylaminobenzenesulfate	grams	2
	Hydroquinone	do	6
	Dry sodium sulfite	do	25
20	Mannamine	do	40
	Potassium bromide	gram	0.5

EXAMPLE 3

Brown developer

25	Water	cc	1000
	Hydroquinone	grams	24
	Dry sodium sulfite	do	60
	Lactamine	do	80
30	Potassium bromide	do	2

EXAMPLE 4

Soft working developer

35	Water	cc	1000
	1 - hydroxy - 4-methylaminobenzenesulfate	grams	15
	Dry sodium sulfite	do	75
	Xylamine	do	80
40	Potassium bromide	do	2

EXAMPLE 5

Reversal developer

Water	cc	1000
1 - hydroxy - 4-methylaminobenzenesulfate	grams	5
Hydroquinone	do	13
Dry sodium sulfite	do	200
Potassium bromide	do	5.5
Ethylglucamine	do	50 10

EXAMPLE 6

Fine grain developer

Water	cc	1000
Para-phenylene diamine	grams	15
Dry sodium sulfite	do	60
Arabinamine	do	5
Potassium bromide	gram	1

EXAMPLE 7

Color developer

Water	cc	1000
Diethyl-para-phenylene diamine	grams	8
Methylglucamine	do	20 25

What we claim is:

1. Photographic developer comprising developing agents and an aliphatic hydroxyalkylamine containing in its molecule at least one alkyl chain having at least two hydroxyl groups combined with different carbon atoms.
2. Photographic developer comprising developing agents and mannamine.
3. Photographic developer comprising developing agents and lactamine.
4. Photographic developer comprising developing agents and methylglucamine.

PAUL GOLDACKER.

GEORG MAISER.

ERNST SCHMITZ-HILLEBRECHT. 40
